UNITED STATES PATENT OFFICE.

FRANK DI GIANNI, OF MUSCATINE, IOWA.

SHELL-GRINDER.

1,109,405.

Specification of Letters Patent.

Patented Sept. 1, 1914.

Application filed February 25, 1914. Serial No. 820,917.

To all whom it may concern:

Be it known that I, FRANK DI GIANNI, a citizen of the United States, residing at Muscatine, in the county of Muscatine and State of Iowa, have invented certain new and useful Improvements in Shell-Grinders; and I hereby declare that the following is a full, clear, and exact description thereof, reference being had to the accompanying drawings, which form part of this specification.

This invention is a novel improvement in machines for grinding irregularly shaped bodies of shell and the like; and its object is to provide a machine which can be easily operated; and in which all the parts are readily adjustable and accessible.

I will explain the invention in detail with reference to the accompanying drawings, and will summarize the invention in the claims following the description.

Figure 1 is a front elevation of the complete machine. Fig. 2 is an enlarged side view thereof. Fig. 3 is a section on line 3—3, Fig. 2. Fig. 4 is a top plan view of the machine showing the different arrangements of the grinder.

The machine has a base plate 1. Mounted upon this base is a swingable frame which consists of a bifurcated casting 2, the lower end of the shank of which is pivoted or hinged on the base; and it is shown as pivoted on stud bolts 3 tapped through lugs 1^a rising from the base 1. The bifurcations 2^a of this frame 2 are bored for the passage of a shaft 4, which is preferably mounted therein by means of ball-bearings, comprising outer races 5, balls 5^b and inner races 5^a. The races 5 are screwed into the outer ends 4^a of shaft 4; in this way the shaft 4 is mounted rotatably in the frame 2 and is also held against longitudinal play therein.

On the shaft 4, intermediate the bifurcations 2^a is fixed a gear 4^c; and collars or disks 4^d may be placed on the shaft at each side of the gear 4^c to fill the spaces between said gear and the adjacent ends of the bifurcations 2^a.

A tapered collar 6 may be placed on one end of the shaft and abut against one of the bifurcations to relieve the shaft of end-thrust, said collar being secured by a set-screw 6^a. On the other end of the shaft is

attached a removable cam 7, which should have an exterior contour conformable to the desired contour of the object which it is desired to make.

The cam 7 may be removably secured on the shaft by means of a screw 7^a. In practice a number of interchangeable cams 7 will be provided with each machine; so that a different shaped article can be ground thereon.

The ball race 5^a at the cam end of the shaft may be secured in position by means of a washer 4^b slidably keyed to the shaft, and a jam nut 4^c screwed on the shaft as shown.

The cam 7 is adapted to contact with an abutment 7^b on the upper end of a bar or bracket 7^c, the foot of which is slotted at 7^d and secured to a lateral extension 1^e of the base 1, by means of set bolts and washers 7^e, so that the abutment 7^b can be adjusted toward or from the shaft 4.

The frame 2 is normally moved to hold the cam 7 in contact with the abutment 7^b by means of a rod 8 pivoted to the frame at 8^a and extending through an eye 8^b in a stud or bar 1^d rising from the base 1 in rear of the frame. A helical expansion spring 8^c is strung on this rod 8 between the upright 1^d and notch 8^e screwed on the outer end of rod 8. The spring being adapted to draw the frame inward and hold the cam 7 in contact with the abutment 7^b.

Attached to the forward side of the frame 2 is a bracket 2ⁿ which extends upwardly to approximately the level of the shaft 4, and it is transversely bored for the reception of a shaft 9 on which is fixed a pinion 9^a that meshes with gear 4^c, and on the outer end of this shaft 9 is a handle 9^b by which said shaft can be turned. When the handle is turned of course shaft 4 will be rotated by the intermeshing of the gears.

On the outer end of the shaft 4 adjacent the collar 6 is a work holder or clamp 10, which may be secured to the shaft 4 by a set-screw 10^a and which is provided with a slot in its inner end adapted to engage a transverse rib 6ⁿ on the adjacent end of the collar 6, so as to cause the cam holder 10 to rotate with the shaft.

The bracket 2ⁿ may be provided with an eye 2^x which may be connected by a rod or cord 2^y with a foot treadle or lever, not shown, so that by depressing said treadle frame 2 may be drawn forward so as to move the shell out of contact with the

grinder, and the cam out of contact with the abutment 7^b, when it is desired to change the cam or adjust or rearrange the shell on the holder; or adjust the abutment.

5 The shell S held by the clamp 10 is adapted to be ground by a vertically disposed grinder G, indicated in Fig. 1, and which is rotated by a suitable means (not shown); or it may be ground by a horizontally disposed grinder G'; indicated in Fig. 4, and operated by means not shown.

The frame may be drawn forward by depressing the treadle (not shown) and the desired cam attached to the shaft, and the object to be ground slipped on the holder 10 or secured thereto as indicated in Figs. 1 and 4. When the treadle is released the spring 8^a swings the frame toward the grinder until it is arrested by the cam 7 engaging the abutment 7^a. The grinding disk is rotated and the object being ground is rotated against the grinder by turning the handle 9^b until it is ground to the same contour as the cam 7, as will be readily understood. By placing a cam 7 of any desired contour on the shaft 4, the shell or object on the holder 10 can be reduced to the same contour.

What I claim is:

20 1. In a shell grinder the combination of a swinging frame pivoted at its lower end on a suitable support and having its upper end bifurcated, a shaft rotatably journaled in and extending through the bifurcations of 25 the frame, a shell holder on one end of said shaft, a shaping cam on the other end of said shaft, an abutment attached to the frame and adapted to be engaged by said cam, a spring connected with said frame and 30 base for normally swinging the frame so as to hold the cam in yielding contact with said

abutment, and means for manually rotating said shaft.

2. In a shell grinder the combination of a base, a swinging frame pivoted to said base, 45 and a shaft rotatably journaled in and extending through the frame, a shell holder on one end of said shaft, a shaping cam on the other end of said shaft, an abutment on the base adapted to be engaged by said cam, 50 a spring for normally swinging the frame so as to bring the cam in contact with said abutment; a gear on said shaft, a manually operable shaft mounted on said frame parallel with the first shaft, and a pinion on the 55 manually operable shaft engaging the gear on the first shaft.

3. In a shell grinder the combination of a base, a Y-shaped frame hinged thereon at its lower end and having a bifurcated upper 60 end, a rotatable shaft journaled in the bifurcations of said frame, a shell holder on one end of the shaft, a shaping cam removably attached to the other end of the shaft, an abutment on the base adjacent said cam, a 65 spring for yieldingly swinging said frame to hold said cam in contact with said abutment, a gear on said shaft, an upstanding bracket attached to the front side of said frame adjacent said pinion, a manually operable shaft journaled in said bracket parallel with the first shaft, and a pinion on the manually operable shaft engaging the gear on the first shaft.

In testimony that I claim the foregoing 75 as my own, I affix my signature in presence of two witnesses.

FRANK DI GIANNI.
